UNITED STATES PATENT OFFICE

2,287,315

COLLAPSIBLE CARRIAGE AND SHACKLE
MOUNTING THEREFOR

Samuel Kroll and Nathan J. Kroll, Chicago, Ill.

Application December 6, 1940, Serial No. 363,755

5 Claims. (Cl. 280—47)

This invention relates to baby carriages and more particularly to the running gear or chassis structure thereof and has for its principal object the provision of an improved construction which will be highly efficient in use and economical in manufacture.

The present invention constitutes an improvement in that shown in our companion application filed on even date hereof and bearing Serial No. 363,754.

An object of this present invention is to compensate for the weight disposed upon the carriage body either by the occupant thereof or from any other source, thus preventing the transposition of this weight to the weaker parts of the chassis structure resulting in preventing the buckling or rupturing of the chassis structure, which buckling or rupturing throws the parts of the chassis structure out of alignment with respect to each other, or otherwise results in too free play between these parts to the detriment and discomfort of the occupant and the operator.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a side sectional detail view of a carriage embodying our invention and shown in collapsed condition;

Fig. 2 is a side part sectional detail view of the carriage in extended position;

Fig. 3 is a fragmentary plan view taken substantially on line 3—3 of Fig. 2;

Fig. 4 is a fragmentary sectional detail view of the same taken substantially on line 4—4 of Fig. 3;

Fig. 5 is a fragmentary sectional detail view of the same taken substantially on line 5—5 of Fig. 4;

Fig. 6 is a fragmentary side sectional detail view of the chassis structure showing a modified form of construction of our invention;

Fig. 7 is a fragmentary sectional detail view of the same taken substantially on line 7—7 of Fig. 6; and

Fig. 8 is a fragmentary sectional detail view of a shackle structure embodying our invention and illustrating a modified form over that shown in Fig. 6.

Referring more particularly to Figs. 1 to 5 inclusive, 10 indicates the wheels of a carriage. These wheels are mounted upon axles 11 and 12. These axles are mounted through bearing structures to be presently described, upon chassis side bars 13. The axle 12 has associated therewith the usual stabilizing device, generally indicated 60

at 14, and comprising bar members secured to the axle 12 as at 15, and an attaching bracket 16 secured to the bottom 17 of the carriage body 18.

Carried by the axles 11 and 12 are shackle structures 19 connected in a manner to be hereinafter set forth to the corresponding end portions of the scissors arm 19', arranged in pairs, with the arms of each pair pivotally connected as at 20 intermediate their end portions and with 10 the upper end portions pivotally secured to the body 18 as at 21.

To corresponding pairs of the scissors arms 19' is adjustably secured a handle 22 locked in extended position by suitable latching mechanism 23, constituting no part of the present invention other than being preferred, though not necessary, in a baby carriage employing our invention.

Each of the shackle structures 19 comprises a U-shaped bar 24, the ends of which are connected as at 25 to the axle with which it is associated. In the limb portions 26 of the shackle 19 are provided elongated slots 27 within which is arranged for slidable movement a shackle pin 28, and to this shackle pin 28 the lower end of the scissors arm 19' with which it is associated, is connected. Bearing upon the bight portion 29 of the shackle bar 24 and held in place by suitable pins 30 are spring members 31, the ends of 30 which are connected as at 32 to the shackle pin 28.

The bearing members for the axles 11 and 12 each comprise an adjustable bearing plate 33 disposed beneath an adjacent portion of the chassis side bar 13 with which it is associated and having side wall portions 34 disposed adjacent the side edges of such chassis side bar, whereby the plate 33 may be guided in its movement longitudinally of said bar 13.

40 Formed in the bar 13 with which this bearing plate 33 is associated, is an elongated slot 35 and operable in this slot 35 is a connecting pin 36, carried by the bearing plate as at 37. Upon this bearing plate 33 forwardly of the pin 36 is the wheel-bearing axle of the carriage. This plate 33 has a reduced end portion 38 projected through an opening 39 formed in a depending lug 40 provided by the chassis side bar. Threaded upon this extended portion of the plate 33 is a wing nut 41. The arrangement is such that by adjusting the wing nut 41 of each of the bearing structures, the relative distance between the axles may be increased or decreased, depending upon the weight imposed upon the chassis parts through the body 18. Thus, it will be apparent that as the child increases in weight, the operator of the carriage may adjust the wing nuts 41, so as to vary the distance between the axles 11 and 12 to compensate for this increased weight, which may be evidenced by an observation of the chassis side bars

when it will be found that as the weight increases their tendency is to buckle. The buckling of these bars is prevented by the use of the bearing structure and spring-compensating shackles hereinbefore described.

The present invention has all the advantages explained in our previous application, hereinbefore identified, and like our previous invention the shackle bars of one of the axles of the present structure may be fixed rather than adjustable.

In Figs. 6 and 7 we have illustrated a modified form of construction over that previously described. In this description the end 42 of each of the scissors arms 19' is pivotally secured as 15 at 43 to a connecting link 44. The lower end of this connecting link 44 carries a pin 45, to which the end portions 46 of shackle springs 47 are secured, the other opposite ends 48 of the shackle springs 47 being secured to the bearing sleeve 20 49 of the wheel-bearing axle.

Formed in the opposite end portions of the connecting link are spaced openings 50 through any one of which is adapted to be projected the shank of a set screw 51. On this connecting link 25 44 is a stop 52 which limits the adjustment of the link relative to the side scissors arm with which it is associated.

The arrangement is such that to compensate for the additional weight imposed upon the 30 chassis structure of the carriage or the looseness of any of the parts of the chassis structure, the operator will remove the set screw 51, adjust the link 54 relative to the scissors arm 19', to a position which it is deemed necessary to compensate for the additional weight. After such adjustment, the set screw 51 is then mounted in its new adjusted position. The advantages of 35 this structure carry with it all the advantages hereinbefore explained, and it will be apparent that this structure is comparatively simple in construction, yet highly efficient in use.

In Fig. 8, we have shown a modified form of construction of the shackle over that shown in Fig. 6. In this connection, we have employed 45 the shackle employed in the structure shown in Figs. 1 to 5 inclusive. Reference to such shackle structure may be had for an understanding of the shackle structure illustrated in Fig. 8, and similar parts are designated by like reference 50 characters.

While we have illustrated and described the preferred form of construction for carrying our invention into effect, this is capable of variation and modification without departing from the spirit of the invention. We therefore do not wish to be limited to the precise details of construction set forth, but desire to avail ourselves of such variations and modifications as come within the scope of the appended claims.

Having thus described our invention, what we claim as new and desire to protect by Letters Patent is:

1. In combination with a carriage running gear structure having side bars, and a wheel-bearing axle, bearing structures for said axle each comprising a bearing plate, means providing slidable adjustable connection between the plate and the side bars, and means for manually adjusting said plate relative to said side bars, said last-named means comprising a threaded portion on said bearing plate and a wing nut threaded thereon, and a spring shackle carried by said axle and adjustable therewith.

2. In combination with a carriage running gear structure having side bars, and a wheel-bearing axle, bearing structures for said axle each comprising a bearing plate, means providing slidable adjustable connection between the plate and the side bars, and means for manually adjusting said plate relative to said side bars, said last-named means comprising a threaded portion on said bearing plate and a wing nut threaded thereon, and a spring shackle carried by said axle and adjustable therewith, and carriage body frame members adjustably carried by said shackle.

3. In a baby carriage of the class described in which there is a chassis structure comprising opposite chassis side bars and a pair of spaced wheel bearing axles extending transversely of the side bars, a carriage body, supporting means for said body comprising opposite pairs of scissors arms having their lower end portions extending to a point substantially below the plane of the longitudinal axis of said axles, spring means carried by the axles and extending downwardly and inwardly between said axles and below said plane and connected to the lower extremities of said scissors arms, and means providing the connection between said spring means and said lower extremities of said scissors arms.

4. In an adjustable axle structure for a baby carriage running gear comprising a chassis structure having parallelly disposed side bars and a wheel bearing axle spanning said side bars, the provision of bearing structures for said axles each comprising, in combination, a bearing plate, said bearing plate being channel-shaped and disposed with the free ends of its flange portions embracing said side bars, said axle extending through the flange portions of said bearing plate between said side bar and the web of said channel-shaped bearing plate, an elongated slot formed in said side bar, pin means affixed to the web of said channel-shaped bearing plate and extending through said elongated slot, and means for manually adjusting said plate relative to said side bars, said last-named means comprising a downwardly extending apertured lip on said side bar adjacent said elongated slot, a threaded portion extending longitudinally from the web of said bearing plate, through said apertured lip, and a wing nut threaded on said threaded portion.

5. In a baby carriage of the class described in which there is a chassis structure comprising opposite chassis side bars and a pair of spaced wheel bearing axles extending transversely of the side bars, a carriage body, supporting means for said body comprising opposite pairs of scissors arms having their lower end portions extending to a point substantially below the plane of the longitudinal axis of said axles, a U shaped shackle having the free end portions of its legs carried by the axles and extending downwardly and inwardly between said axles below said plane, elongated slots formed in the legs of said U shaped shackle, a shackle pin arranged to slide in said slots and spanning the legs of said U shaped shackle, the lower extremities of said scissors arms arranged between said shackle pin, and spring means arranged between said shackle pin and the bight portion of said U shaped shackle.

SAMUEL KROLL.
